UNITED STATES PATENT OFFICE.

ISAAC W. DRUMMOND, OF NEW YORK, N. Y.

PAINT-TUBE.

No. 801,227.

Specification of Letters Patent.

Patented Oct. 10, 1905.

Application filed February 28, 1905. Serial No. 247,712.

To all whom it may concern:

Be it known that I, ISAAC W. DRUMMOND, a citizen of the United States, and a resident of the borough of Manhattan, city, county, 5 and State of New York, have invented a new and useful Improvement in Paint-Tubes, of which the following is a specification, reference being had to the accompanying drawings, in which—

10 Figure 1 illustrates a vertical sectional view of a paint-tube embodying my invention. Figs. 2 and 3 illustrate modified forms thereof.

Heretofore paint-tubes have been made with threads formed in the metal at the mouth of 15 the tube, with which corresponding threads cut in the interior of a suitable metallic cap engaged, whereby the cap was screwed down to close the mouth of the tube, and a wafer or thin piece of material—cork, for example—has been sometimes employed in the bottom of the cap to additionally seal the joint. It frequently happens, however, that notwithstanding the stated construction and attempt 20 to effectively seal the tube the oils from the paint or other material inclosed within the tube will in course of time, owing to atmospheric or other conditions, exude from the tube, soiling the outside thereof, thus badly defacing the goods and making them more or 25 less unsalable.

30 Tubes for containing adhesive material having a thin easily-perforated disk or film of metal over the mouth or opening have also been constructed, the thin plate of metal being perforated or punctured at the time of use, so that after the mucilage or equivalent material has been expelled from the tube at 35 each use by suitable pressure thereon the material remaining just at the perforation or opening quickly dries, which again seals the device, so that further escape of the contents 40 is impossible, and it is maintained in suitable condition for subsequent use.

The tubes last described are unsuited for 45 the paint trade, because the paint will not dry within sufficient time to reseal the package after it has been once opened. On the contrary, it remains soft in some instances for days together, and during the interim the 50 material will exude spontaneously in many cases, and also the tube will be subjected to more or less pressure during its handling, thus increasing the exudation, whereupon not only is the paint or other material wasted, but 55 all surrounding objects smeared and defaced therewith. Moreover, the orifice made by

merely puncturing the soft-metal diaphragm or sealing-piece is apt to be too small for effective use by artists or other users of paints.

The purpose of my present invention, therefore, is to so construct a tube as that it shall possess all the advantages and none of the disadvantages above referred to.

Referring to Fig. 1, A represents the body of the tube, which is of the kind universally 65 made of a single piece of homogeneous and ductile metal, as is well known, and which is closed at the bottom B in the usual manner. C is the threaded stem or upper extremity of the tube. D is the usual threaded cap. E is 70 an outwardly or upwardly projecting part of the metal forming the tube, which may be made somewhat thinner than the rest of the metal composing the stem C, so that when it is desired to use the contents of the tube this 75 upwardly-projecting part E may be readily removed wholly or partly by any suitable cutting instrument—as, for instance, the blade of a penknife, a pair of shears, or its equivalent—so that an opening substantially as large 80 as that through the stem C may be afforded for the egress of the paint.

In Fig. 2 I show a construction substantially the same as that of Fig. 1, except instead of being dome-shaped the upwardly-extending 85 thin metal (shown at F) is cylindrical in outline.

In Fig. 3 I show still another modification in which the sealing-strip G does not project upwardly above the upper edge of the threaded 90 part of the stem C, but, on the contrary, is horizontal therewith.

I prefer the construction shown in the other two drawings because, owing to the upward projection of the thin removable sealing-piece, 95 it is more easy to remove it; but the form shown in Fig. 3 is nevertheless useful, because the point of a knife-blade or one blade of a pair of shears will readily cut out the thin sealing-piece when it is desired to use the 100 contents of the tube.

It will be observed that under my construction, during storage and while in the store of the merchant and also while in the user's hands, unopened, the tube is absolutely, indeed hermetically sealed, so that no possibility exists of exudation of any of the contents thereof. Therefore the article remains clean, slightly, and attractive. When desired, however, the sealing-piece may be wholly or partly 105 removed in an instant and an opening of sufficient area to best serve the purpose is af-

forded, and from that time forward the contents of the can will be securely retained by replacing the cap as heretofore. Should slight exudation of the contents of the tube occur 5 while in use in the hands of the artist or artisan, no harm will result, for such exudation will be exceedingly slight, if any, because of the presence of the cap, and a slight smearing of the mouth or upper part of the tube is of no 10 consequence to the users thereof for they are accustomed to more or less smearing of their utensils with paints, oils, &c.

My tubes are preferably made of tin, but may be made of any other suitable metal or 15 material. For large tubes, which would be expensive if made of tin, I make up a tin and lead alloy and sometimes make them entirely of lead.

The cap, as shown, is preferably threaded 20 to the stem; but obviously other means of attaching the two suitably together may be substituted for the threads.

It will be obvious to those who are familiar 25 with this art that modifications may be made

in the details of construction without departing from the essentials thereof. I therefore do not limit myself to the details described and illustrated.

I claim—

1. A paint-tube embodying a body part, a 30 stem, a removable sealing-piece which projects outwardly beyond the stem proper and independently seals the structure, all composed of a single homogeneous piece of metal, and a cap for the stem.

2. A paint-tube embodying a body part, an 35 exteriorly-threaded stem, a removable sealing-piece which projects beyond the stem, all of said parts being composed of a single homogeneous piece of metal, and a threaded cap 40 adapted to engage with the stem.

In testimony whereof I have signed my name to this specification in the presence of two subscribing witnesses.

ISAAC W. DRUMMOND.
